UNITED STATES PATENT OFFICE.

EDWARD F. JOHNSON, OF JERSEY CITY, NEW JERSEY.

MEANS FOR OPERATING AND LOCKING SCUTTLE-COVERS.

SPECIFICATION forming part of Letters Patent No. 706,829, dated August 12, 1902.

Application filed May 14, 1902. Serial No. 107,286. (No model.)

To all whom it may concern:

Be it known that I, EDWARD F. JOHNSON, a citizen of the United States, residing at Jersey City, in the county of Hudson and State 5 of New Jersey, have invented certain new and useful Improvements in Means for Operating and Locking Scuttle-Covers, of which the following is a full and complete specification, such as will enable those skilled in the 10 art to which it appertains to make and use the same.

The object of this invention is to provide an improved apparatus for opening a scuttle-cover and also for closing and locking the 15 same, a further object being to provide an apparatus of this class which may be applied to a transom, skylight, and other device of this class.

The invention is fully disclosed in the following specification, of which the accompanying drawings form a part, in which the separate parts of my improvement are designated by the same reference characters in each of the views, and in which—

25 Figure 1 is a transverse section of a scuttle provided with my improvement; Fig. 2, a section of the cover of the scuttle on the line 2 2 of Fig. 1, and Fig. 3 a section of the frame of the scuttle on the line 3 3 of Fig. 1.

30 In the drawings forming part of this specification I have shown at *a* the framework of a scuttle, to which is hinged at *a*³ a cover *a*³, said cover being preferably provided with downwardly-directed end and side plates *a*⁴, 35 and in the practice of my invention I secure to one end of the scuttle-frame *a* a plate *b*, to which is pivoted at *b*² two of the side arms *c*² of a toggle-lever *c*. One of the side arms *c*² of the toggle-lever *c* is extended, as shown at 40 *c*³, and connected therewith in the form of construction shown in the drawings is a rod *c*⁴, similar to an ordinary transom-operating rod, and this rod is passed through a keeper *c*⁵, and by means thereof the toggle-lever *c* 45 may be operated. One of the side arms *c*⁶ of the toggle-lever *c* opposite the side arms *c*² is projected, as shown at *c*⁷, in a direction opposite to that of the projection *c*³ of one of the side arms *c*² and is pivoted to a link *d*,

50 which is pivoted at *d*² to a plate *d*³, which is secured to the cover *a*³, and said link *d* is provided with a pin *d*⁴, which moves in a slot *d*⁵

in the plate *d*³. I also provide a bar *e*, which is secured to end pieces *e*², which are hinged to the cover *a*³ at *e*³, and secured to the opposite ends of the bar *e* are dogs *e*⁴, which are adapted to engage with catches *e*⁵, secured to the corresponding side of the scuttle-frame *a*, and secured to the cover *a*³ at *e*⁶ is a spring *e*⁷, which is adapted to bear on one of the 55 said dogs or on the bar *e* and to force both of said dogs into engagement with the catches *e*⁵, and connected with one of said dogs at *g* is a link *g*², which is pivotally connected with an extended member *g*¹ of one of the side arms 60 *c*⁶ of the toggle-lever *c* and also with the link *d*.

The normal position of the cover *a* is that shown in dotted lines in Fig. 1, and in this position the cover is locked by the dogs *e*⁴, 70 which engage with the catches *e*⁵, and whenever it is desired to raise the cover *a*³ the rod *c*⁴ is pulled downwardly. This operation expands the toggle-lever *c* and releases the dogs from the catches *e*⁵ and at the same time 75 raises said cover *a*³, and it will be understood that the cover *a*³ will be held at any desired point of elevation by means of the rod *c*⁴, which passes through the keeper *c*⁵, and any desired means may be provided for securing 80 said rod in said keeper, and when the rod *c*⁴ is released the cover *a*³ will again drop into the closed position, as shown in dotted lines in Fig. 1, and will be locked in this position.

Instead of the rod *c*⁴ a cord or any other 85 device may be connected with the extension *c*³ of one of said members *c*² of the toggle-lever *c*, and other changes in and modifications of the construction herein described may be made without departing from the 90 spirit of my invention or sacrificing its advantages.

Having fully described my invention, what I claim as new, and desire to secure by Letters Patent, is—

95 1. The herein-described means for opening, closing and locking a scuttle-cover, transom, skylight or similar device, comprising a toggle-lever, two of the side arms of which are pivoted to the framework and one of which is projected and provided with an operating device, one of the opposite side arms of said toggle-lever being also projected and pivotally connected with a link which is pivoted 100

to a plate secured to the scuttle-cover, transom, or skylight, spring-operated locking-dogs hinged to said cover, transom or skylight, and catches secured in the frame and 5 adapted to be engaged by said dogs, said dogs being also in operative connection with said link, substantially as shown and described.

2. The herein-described means for operating a scuttle-cover comprising a toggle-lever 10 two of the side arms of which are pivoted to the framework of the scuttle and one of which is projected and provided with an operating device one of the opposite side arms of said toggle-lever being also projected and pivotally connected with a link which is pivoted 15

to a support secured to said cover and a spring-operated dog hinged to said cover and adapted to engage a catch secured in said framework, said dog being also in connection with said link, substantially as shown and 20 described.

In testimony that I claim the foregoing as my invention I have signed my name, in presence of the subscribing witnesses, this 10th day of May, 1902.

EDWARD F. JOHNSON.
